UNITED STATES PATENT OFFICE.

JOHN B. DOSS, OF WINGATE, INDIANA.

MAIL-BAG HASP-LOCK.

1,151,673.

Specification of Letters Patent. Patented Aug. 31, 1915.

Application filed May 2, 1914. Serial No. 835,945.

To all whom it may concern:

Be it known that I, JOHN B. DOSS, a citizen of the United States, residing at Wingate, in the county of Montgomery and State of Indiana, have invented certain new and useful Improvements in Mail-Bag Hasp-Locks, of which the following is a specification.

The object of this invention is to provide a hasp lock, particularly well adapted for use on mail bags and in like connection, which can be very simply and inexpensively manufactured, and has the part thereof so constructed and arranged that the danger of breakage or injury to the lock, due to the rough usage usually accorded such locks, is almost entirely precluded.

This invention also has for its object to provide a lock of this character, which, while it can be applied and locked by any person without the use of special implement, cannot be opened without the use of a special key.

With other objects in view, which will be referred to, my invention consists in the peculiar combination and novel arrangement of parts, such as will be hereinafter more fully described in connection with the accompanying drawing and more particularly pointed out in the appended claim.

In the drawing:—Figure 1 shows the upper end of a bag closed and with my hasp lock in place. Fig. 2 is a sectional view on the line 2—2 of Fig. 3. Fig. 3 is a longitudinal sectional view on the line 3—3 of Fig. 2. Fig. 4 is a view in perspective of one of the blocks used to hold the lock in place within the hasp. Fig. 5 is a view in side elevation showing one form which the key used to release the lock might take.

The hasp in its body portion comprises a top 1 and a bottom 2 which are connected together around their edges by a rim 3, to form a casing. The top and bottom members 1 and 2 of the casing have longitudinal slots 4 and 5, respectively, formed therethrough to be in transverse alignment and the spring locking arms 6 and 7 are mounted in the casing to lie on either side thereof adjacent the slots 4 and 5. The spring arms 6 and 7 are connected to the blocks 11 and 12, and these blocks are in turn secured rigidly within the casing by the rivet 13 which may be also used to secure the top and bottom member 1 and 2 of the casing connected with the rim 3. A pin 8 is secured to the bottom member 2 of the casing to

extend upwardly therefrom near the outer end and the arms 6 and 7 are brought around at 9 and 10 to fit adjacent this pin 8.

The hasp casing composed of the members 1, 2 and 3 is, in the adaptation disclosed, illustrated as connected with a strap 14 provided to be passed around the top of the mail bag after this top has been brought together as shown in Fig. 1, by a hinge connection 15. 60 The spring arms 6 and 7 each have a projection 16 formed from the inner side thereof to extend to a position within the opening through the slots 4 and 5, as better shown in Fig. 2. A staple 17 of a dimension to fit 65 through the slots 4 and 5 is secured to the member with which the hasp is to be locked, and in the present instance it will be understood of course that this staple is connected with one end of the strap 14 while the hasp 70 is connected with the opposite end. 75

In use, the hasp is placed with relation to the staple 17 so that this staple comes within the slot 5, then by exerting pressure upon the hasp the projections 16 are brought to 80 bear against the staple 17 and are forced from the path of the staple against the tension of the spring arms 6 and 7. It will be understood that this staple 17 might be made beveled on each side so that it would be 85 wedge-shaped where it comes between the projections 16, or that the outer edges of these projections 16 might be beveled to present an incline surface to the staple as it is inserted through the slot 5 thus making 90 the hasp more readily placed over the staple. When the projections 16 have passed over the body of the staple 17 they spring back to occupy the position shown in Fig. 2, so 95 that they rest and engage within the loop of the staple and prevent removal of the hasp therefrom. The top member 1 of the casing of the hasp is provided with a keyway 18 directly above the point of disposition of the pin 8 and the key 19 adapted to release 100 the hasp from its locked position can be inserted through this keyway 18 to a point between the end 9 and 10 of the spring arms 6 and 7. When the key 19 is inserted within 105 the casing and turned, it engages with the end 9 and 10 and forces the spring arms 6 and 7 back toward the sides of the casing against their spring tension thus removing the projections 16 from their position within the loop of the staple 17 and leaving the 110 staple 3 to be withdrawn from its position through the slots 4 and 5.

From the foregoing it will be seen that I have provided a hasp having an internally arranged lock so constructed that it may be brought into locked relation with a staple 5 without the use of special implements, yet requires a special key that it may be released from the staple.

While I have herein shown and described one specific form of my invention, it will be 10 understood that slight changes might be made in the form and arrangement of the parts without departing from the spirit and scope of my invention, and hence I do not 15 wish to be limited thereto except for such limitations as the claim may import.

I claim:—

In a hasp lock; a hasp casing provided with a slot transversely therethrough through 20 which a staple may be inserted and passed, a pair of bow-leaf spring arms perforated at

their one end and at the opposite end shaped to have key-receiving portions, each of said arms provided with a staple-engaging portion within the bow thereof, slotted blocks rigidly mounted within said casing on opposite sides thereof within which the perforated ends of said bow-spring members are received, and pins passed through said blocks and through the perforations of said spring members to hold the same rigidly 25 secured within the blocks and with the staple-engaging projections thereof within the opening through the casing.

In testimony whereof I affix my signature in presence of two witnesses.

JOHN B. DOSS.
